A. E. RHOADES

FILLING CARRIER SUPPORT FOR LOOMS

Filed April 18, 1922

Fig. 1.

Fig. 2.

Inventor:
Alonzo E. Rhoades
by Heard Smith & Tenant
Atlys.

UNITED STATES PATENT OFFICE.

ALONZO E. RHOADES, OF HOPEDALE, MASSACHUSETTS, ASSIGNEE TO DRAPER CORPORATION, OF HOPEDALE, MASSACHUSETTS, A CORPORATION OF MAINE.

FILLING-CARRIER SUPPORT FOR LOOMS.

Application filed April 18, 1922. Serial No. 554,789.

To all whom it may concern:

Be it known that I, ALONZO E. RHOADES, a citizen of the United States, and resident of Hopedale, county of Worcester, State of Massachusetts, have invented an Improvement in Filling-Carrier Supports for Looms, of which the following description, in connection with the accompanying drawing, is a specification, like characters on the drawing 10 representing like parts.

This invention relates to the construction of a filling carrier support for an automatic filling replenishing loom and the object of the invention is to provide a construction of 15 a strong and durable nature.

The object of the invention is further to provide such a construction in which pivotal or rocking movement of the support will be permitted and facilitated under all conditions of use.

The object of the invention is further to provide a simple and efficient construction in which the filling carrier support may be readily removed and replaced when repair 25 or replacement is required.

The nature and objects of the invention will appear more fully from the accompanying description and drawing and will be particularly pointed out in the claims.

In the drawings:

Fig. 1 is an end elevation partially in vertical cross section of so much of an automatic filling replenishing loom as is necessary to a disclosure of the invention;

Fig. 2 is a view in plan and partially in transverse cross section of a portion of the construction shown in Fig. 1.

This invention relates to the yielding and pivoted or rocking filling carrier support 40 which is a usual feature of an automatic filling replenishing loom. The loom, a portion of which is illustrated to disclose a preferred form of the present invention, is that of the well-known Northrop type, and as this type of loom is familiar to those skilled in the art and as the present invention relates only to the filling carrier support no extended description of the loom or its operation is necessary.

Such a loom comprises the usual loom frame 1, breast beam 2, lay 3, a magazine or hopper for containing the supply of fresh filling carriers, and the transerrer 4 for transferring a fresh filling carrier 5 in the

hopper to the shuttle 6 on the lay when the 55 running filling has become exhausted or depleted.

The magazine or hopper comprises a stand 7 usually secured to the breast beam at one end of the loom and a plate 8 rising vertically from the hopper stand. The foremost fresh filling carrier 5 is brought into position by the hopper ready for discharge into the shuttle when replenishment is called for and is usually brought up against a guide 60 or abutment 9 by which it is guided into the shuttle upon replenishment taking place under the action of the transerrer 4.

The filling carrier 5 in this position is usually supported on the side opposite the 70 abutment 9 by a yielding filling carrier support which yields when the transfer takes place to permit the filling carrier to pass downwardly into the shuttle. The action of the transerrer is given through the movement of the lay and is that of a sudden sharp, blow so that the filling carrier is forced down with considerable force and the filling carrier support is, therefore, swung downwardly by the same sudden force.

The present invention presents a filling carrier support which will operate efficiently and readily under these conditions and which will present a strong and durable construction as little liable to breakage or injury as is possible. One feature of the invention consists in providing extended bearings for the filling carrier support so that it will not tend to twist and break the plate upon which it is mounted when it is rocked under the 85 blow of the transerrer.

Another feature of the invention resides in the construction by which the support may be readily removed and replaced.

The filling carrier support is frequently 95 subjected to great strain by reason of the filling carrier being presented in an improper position by the hopper on the support and not infrequently the parts become 100 jammed and broken. The present invention reduces danger from such happenings to a minimum.

In the preferred form of the invention the plate 8 of the hopper is provided with the boss 10 preferably projecting at each side of the plate so as to present a boss of substantial length. This boss 10 is internally threaded as shown in Fig. 2 and this

threaded portion of the bore of the boss may as shown extend, if desired, only through a portion of the bore. As illustrated the boss 10 is threaded in from the right hand end 5 leaving the exit portion 11 unthreaded and consequently of the original diameter of the bore into which the threaded portion is cut.

A long journal shaft is provided having end bearing sections 12 and 13 and an intermediate threaded section 14 fitting the threaded portion of the boss. The right hand end of this shaft is preferably made polygonal so that it may be operated by a wrench or key. The shaft is screwed into place from the right hand end in the construction illustrated and the bearing section 12 is made of a diameter slightly less than the diameter of the bore or the exit portion 11 of the bore of the boss 10. Hence when 10 the shaft is screwed into place it will be locked by the jamming of the threaded portion as it reaches the end of the threaded portion of the boss. The bearing section 13 of the shaft is preferably also of greater 15 diameter than the internal diameter of the threaded boss 10 so that the shaft will again be locked when screwed into place by the unthreaded section 13 engaging the right hand end of the boss 10. When the bearing section 13 is of this greater diameter then it is not necessary for the locking of the threaded section to take place at the exit end of the boss 10 but preferably the 20 construction is as illustrated.

The filling carrier support is formed on a yoke-shaped frame 15, one arm 16 of which constitutes the filling carrier support proper extending normally in a generally 25 horizontal position into the path of the discharging filling carrier 5. The other arm 40 17 of the yoke-shaped frame extends upwardly and is bifurcated at 18 to pass over a stud 19 and engage the head 20 of the stud. This stud slides in a lug 21 projecting 45 from the plate 8 and a spring 22 is located between the lug and the head 25 of the stud so as to produce the required yield in the rocking or pivotal movement 50 of the frame 15 in a well-known and familiar manner.

The yoke-shaped frame 15 is provided on its two arms with aligned bearings adapted 55 to fit and journal upon the respective bearing sections of the journal shaft. These bearings in the preferred form of the invention extend into and through elongated bearing bosses 24 and 25 projecting externally from the arms of the yoke-shaped frame as illustrated.

To assemble the parts the yoke-shaped 60 frame is placed in position straddling the boss 10 on the plate 8 and the shaft 15 is then inserted from the right hand end through the aligned bearings and screwed 65 into place until it is locked firmly in the

boss 10. To remove the parts it is only necessary to unscrew and remove the shaft.

It will thus be seen that long extended bearings are provided for the filling carrier support so that it is steadied in its movement and even when a sudden and heavy blow is applied to it under unusual conditions such as due to a mispositioned filling carrier its yielding rocking movement will be accurately insured and danger of jamming or breakage reduced to the minimum.

Having thus described my invention what I claim as new and desire to secure by Letters Patent, is:

1. In an automatic filling replenishing loom a hopper plate having an internal threaded boss, a journal shaft having end bearing sections and an intermediate threaded section fitting the threaded boss, the diameter of one bearing section being less, and the diameter of the other bearing section being greater, than the internal diameter of the threaded boss whereby when the shaft is screwed into the boss it is locked in place, and a yoke-shaped frame, one arm of which constitutes the filling carrier support, the said frame straddling the hopper plate boss and provided with aligned bearings on its arms journalled respectively on the bearing sections of the journal shaft.

2. In an automatic filling replenishing loom the construction defined in claim 1 in which the yoke-shaped frame is provided with elongated bosses projecting externally from its arms and in which are formed the bearings for the journal shaft.

3. In an automatic filling replenishing loom a hopper plate having a boss internally threaded through a portion of its bore with the exit portion of the bore unthreaded, a journal shaft having end bearing sections and an intermediate threaded section fitting the threaded portion of the boss, the diameter of one bearing section being less than the diameter of the unthreaded portion of the said boss, whereby when the shaft is screwed into the boss with the said bearing section projecting through the unthreaded exit portion of the boss it is locked in place, and a yoke-shaped frame, one arm of which constitutes the filling carrier support, straddling the hopper plate boss and provided with aligned bearings on its arms journalled respectively on the bearing sections of the journal shaft.

4. In an automatic filling replenishing loom the construction defined in claim 3 in which the yoke-shaped frame is provided with elongated bosses projecting externally from its arms and in which are formed the bearings for the journal shaft.

In testimony whereof, I have signed my name to this specification.

ALONZO E. RHOADES.
